UNITED STATES PATENT OFFICE.

ROBERT L. LAIRD, OF DALLAS, TEXAS.

CIGARETTE CASE.

Application filed January 27, 1928. Serial No. 249,926.

This invention has reference to a container or case especially designed for containing cigarettes or the like articles, an important object of the invention being to provide means whereby the cigarettes may be readily and easily ejected when it is desired to remove a cigarette from the case.

An important object of the invention is to provide a case of this character which will 10 protect the cigarettes against being crushed or broken while they are being removed.

With the foregoing and other objects in view which will appear as the description proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

Referring to the drawing:

Figure 1 is a longitudinal sectional view through a cigarette case constructed in accordance with the invention.

Figure 2 is an elevational view the cover being broken away.

Figure 3 is a sectional view of the case taken on line 3—3 of Figure 1.

Figure 4 is a plan view thereof, the cover being partly broken away.

Referring to the drawing in detail, the body portion of the case is indicated generally by the reference character 5, and as shown 35 a partitioning member 6 is positioned in the body portion and divides the body portion into a cigarette containing compartment 7 and an ejector compartment 8.

Bolted on one end of the body portion 5 is 40 a cover 9 that is supplied with an opening to receive the shaft 10 that also extends through a central opening in the partition 6. This shaft 10 provides a support for the rotary cigarette carrier 11 which is formed with cut 45 out portions 12 extending from the outer edge thereof and terminating at points adjacent to the center of the carrier, the cut out portions defining pockets for the reception of the cigarettes, which are indicated at 13.

Leaf springs 14 are secured within the cut 50 out portions and have curved outer extremities 15 that engage the innermost cigarettes and normally urge the cigarettes outwardly so that the cigarettes will lie opposite to the discharge opening of the casing to the end 55 that they may be ejected from the casing.

In one end of the rotary carrier, and arranged near the inner ends of the cut out portion, are depressions 16 that receive the lug 17 at the outer end of the spring finger 18 which is secured to the partition 6, and which extends through an opening in the partition. By reason of the lug 17 engaging within the 60 depressions 16, it will be seen that the rotary carrier will be held in its proper position to permit the cigarettes to be ejected.

The shaft 10 is movable through the central opening 19 of the rotary carrier, which opening is formed with lateral offsets to accommodate the lugs 20 secured on the shaft 70 10, so that the shaft may be rotated to rotate the rotary carrier, and the shaft may be slid longitudinally of the rotary carrier to eject a cigarette therefrom.

Secured to the inner end of the shaft 10 is 75 an arm 21 which extends laterally therefrom and has a right angled extremity 22 normally resting within the opening 23 of the partition 6. The reference character 24 designates a coiled spring that surrounds the shaft 10 and has one end thereof resting against the partition 6, while the opposite end engages the arm 21 to force the arm against the nut 25. The action of this spring 24 is to hold the shaft 10 in the position as shown by 80 Figure 1.

A filling opening is formed in the cover 9 which filling opening is closed by the pivoted closure 26, and it will be seen that by rotating the shaft 10, the rotary carrier may be 85 moved to bring the cigarette receiving compartments opposite the filling opening where they may be filled.

The reference character 27 designates an 90 opening in the cover 9 through which the cigarettes are thrust by the ejector, there being provided spring fingers 29 adjacent to the opening to grip the cigarette and hold it until it may be removed.

In the use of the device, the shaft 10 is 95 rotated to bring a cigarette compartment before the discharge opening. With the carrier in this position, the shaft 10 is pulled whereupon the right angled end 22 of the arm 21 passes through the opening 23 of the partition 6 where it engages the cigarette in the compartment adjacent to the arm 21 to force the cigarette through the opening 27, where it may be removed readily.

In the form of the invention as illustrated 100 by Figure 3 of the drawing, the cigarette case includes the body portion 30 in which the 105

rotary carrier 31 is mounted, the rotary carrier 31 being of the same general construction as the carrier 11 shown in the former figures of the drawing.

- 5 A partition 32 is mounted in the body portion and provides a rest for the rotary carrier 31 through which the shaft 33 extends, the shaft 33 having lateral enlargements 34 to move in lateral offset portions of the bore 10 35 of the rotary carrier 31. The lower end of the shaft 33 rests against one end of the arm 36, at 37, the arm 36 being pivotally supported at the lower end of the arm 38, the opposite end of the arm 36 contacting with 15 the ejector 39 that is normally held in its inactive position by means of the coiled spring 40 that surrounds it.

As shown by Figure 3 the ejector 39 has its upper end resting within the opening 41 or 20 at a point directly under the cigarette to be ejected and which has been moved opposite to the discharge opening of the cover.

When it is desired to remove a cigarette, it is only necessary to force the shaft 33 downwardly rocking the arm 36 to cause the ejector 25 39 to move upwardly under a cigarette to cause the cigarette to be forced through the discharge opening where it may be removed.

An ash tray indicated at 42 provides the 30 base for the case, to hold the case in its upright position at all times.

I claim:

1. A cigarette container including a body portion, a rotary cigarette carrier mounted 35 within the body portion, said carrier having a bore formed therethrough and having offsets, a shaft extending through the bore, lugs on the shaft disposed within the offsets, to rotate the carrier when the shaft is rotated, an 40 ejector operated by the shaft and said ejector adapted to engage a cigarette contained in the carrier to force the cigarette from the carrier.

2. A cigarette container including a body 45 portion, a rotary cigarette carrier mounted within the body portion, said carrier having a bore formed therethrough, a shaft disposed in the bore, means for transmitting rotary movement of the shaft to the carrier, an 50 ejector operating at one end of the carrier for ejecting a cigarette from the container,

and said shaft adapted to slide through the bore to operate the ejector.

3. A cigarette container including a body portion, a rotary cigarette carrier mounted 5 within the body portion, an ejector operating at one end of the carrier, a shaft extending through the carrier, means for mounting the shaft in the carrier to rotate the carrier, and said shaft adapted to be moved to operate the ejector to eject a cigarette from the container.

4. A cigarette container including a body portion having a discharge opening a rotary carrier operating in the body portion, a shaft extended through the carrier, said shaft adapted to slide through the carrier, said carrier having cigarette pockets, for containing cigarettes, means for connecting the shaft to the carrier to rotate the carrier to bring a cigarette pocket before the discharge opening, and an ejector operating at one end of the carrier for ejecting a cigarette through the discharge opening, and means for urging cigarettes laterally within the pockets.

5. A cigarette container including a body portion having a discharge opening, a rotary carrier within the body portion, said carrier having pockets to receive cigarettes, means in the pockets for moving cigarettes laterally at a point directly under the discharge opening, an ejector operating at one end of the carrier, a shaft for rotating the carrier, and said shaft adapted to operate to move the ejector to force a cigarette through the discharge opening.

6. A cigarette container including a body portion, said body portion having a discharge opening a rotary carrier operating in the body portion and having pockets to receive cigarettes, a shaft for rotating the carrier to bring the pockets into registry with the discharge opening, means for restricting movement of the carrier, and an ejector operated by the shaft for ejecting a cigarette from the carrier and through the discharge opening.

In testimony that I claim the foregoing as my own, I have hereto affixed my signature.

ROBERT L. LAIRD.
